UNITED STATES PATENT OFFICE.

JOSEPH T. CRAW, OF JERSEY CITY, NEW JERSEY, ASSIGNOR OF ONE-HALF
TO ROBERT P. BROWN AND EDWARD L. BAILEY, OF PHILADELPHIA,
PENNSYLVANIA.

DESIGN FOR A BLANK FOR PAPER BOXES.

SPECIFICATION forming part of Design No. 33,941, dated January 22, 1901.

Application filed December 24, 1900. Serial No. 40,989. Term of patent 7 years.

To all whom it may concern:

Be it known that I, JOSEPH T. CRAW, a citizen of the United States, and a resident of Jersey City, in the county of Hudson and State 5 of New Jersey, have invented and produced a new and original Design for a Blank for Paper Boxes, of which the following is a specification, reference being had to the accompanying drawing, forming a part thereof, in which 10 is represented a plan view of a blank embodying the features of my design.

The design consists in the longitudinal curvature of the blank and in the consecutive arrangement of the approximately rectangular panels A, B, C, and D and the sealing-flap d at the outer side of the panel D, together with the substantially triangular panels A', 15 B', C', and D', which appear connected with the end portions of the panels A, B, C, and D.

The auxiliary panels A', B', C', and D' present 20 end lines more or less inclined, and at one side of the auxiliary panel D' a sealing-flap d' occurs, coinciding with the flap d, while at the opposite edge of the auxiliary panel C' another sealing-flap c appears. 25

Having thus described my invention, I claim as new, and desire to secure by Letters Patent—

The design for a blank for paper boxes herein shown and described. 30

In testimony whereof I have signed my name to this specification in the presence of two subscribing witnesses.

JOSEPH T. CRAW.
